UNITED STATES PATENT OFFICE.

THEODORE HUBERT, OF ROSELLE, NEW JERSEY, ASSIGNOR, BY MESNE ASSIGNMENTS, TO AMERICAN CIRCULAR LOOM COMPANY, OF BOSTON, MASSACHUSETTS, A CORPORATION OF MAINE.

MAKE-AND-BREAK DEVICE FOR IGNITION SYSTEMS.

1,050,461.

Specification of Letters Patent. Patented Jan. 14, 1913.

Application filed July 6, 1910. Serial No. 570,548.

To all whom it may concern:

Be it known that I, THEODORE HUBERT, a citizen of the United States, and resident of Roselle, in the county of Union and State of New Jersey, have invented certain new and useful Improvements in Make-and-Break Devices for Ignition Systems, of which the following is a specification.

The object of my invention is to provide improved means for rotatively supporting the make and break devices with respect to the magneto and to permit ready removal and replacement of said devices when required.

15 A further object is to provide certain improvements in parts of the circuit of the magneto.

My invention comprises novel details of improvement and combinations of parts that 20 will be more fully hereinafter set forth and then pointed out in the claims.

Reference is to be had to the accompanying drawings forming part hereof, wherein, Figure 1 is a front view of a portion of a 25 magneto illustrating my improvements in operating position; Fig. 2 is a similar view illustrating the manner of adjusting the parts for removal of the make and break devices; Fig. 3 is a front view of parts, the 30 make and break devices of Figs. 1 and 2 being removed; Fig. 4 is a section on the line 4, 4, in Fig. 1 showing the protecting cap, and Fig. 5 is a section substantially on the line 5, 5, in Fig. 1.

35 In the drawings, the numeral 1 indicates a front support or plate of a magneto, (main parts of the magneto not being illustrated as forming no substantial part of my present improvements), and at 2 is an insulating 40 ring or plate mounted to rotate or rock upon support 1. To this end I have shown support 1 provided with a hub portion 1^a receiving a corresponding centrally disposed opening of insulating plate 2 (see Fig. 4), 45 whereby said plate is removably supported to rotate or rock upon said hub. Hub 1^a is shown provided with an opening 1^b receiving shaft 3 of the magneto such as its armature, having actuating cam 4 arranged in 50 any well known manner. Plate 2 is shown provided with projections 2^a either or both of which may be utilized for rocking said plate, as by being connected with any suitable controlling device in any well known

or desired manner. At 5 are guides or 55 latches carried by plate 1 and adapted to coact with projections 2^a to rotatably retain plate 2 in operating position upon hub 1^a. The guides or latches 5 are shown movably supported upon plate 1 by screws or pivots 60 6, and held in set position by screws 7 threaded into plate 1, for convenience latches or guides 5 being shown provided with recesses 5^a to receive screws 7. In the normal positions of the parts projections 2^a play between plate 1 and guides 5, and said guides are of sufficient length to permit plate 2 to have the required rocking motion while retained in position by said guides. Yet plate 2 may be turned so far in one direction or 65 the other as to enable one of the projections 2^a to pass beyond the adjacent guide 5 (see Fig. 2). To remove or apply plate 2 the same is turned sufficiently far in one direction to enable one of the guides 5 to be 70 drawn outwardly away from the corresponding projection 2^a, and then plate 2 is turned in the reverse direction sufficiently far to carry the other projection 2^a beyond the free end of the corresponding guide 5, as shown 75 in Fig. 2, whereby plate 2 may be removed from hub 1^a and again replaced thereon. When so replaced plate 2 will next be turned to carry its projection 2^a sufficiently high to enable the corresponding guide 5 to be 80 swung over and locked in the position shown in Fig. 1, and then the projections 2^a of said plate may again play in the normal operating 85 position with respect to guides 5 as illustrated in Fig. 1.

90 Plate 2 is shown carrying the make and break rockers 8 pivotally supported upon pins 9 projecting from bases 9^a secured on plate 2, and rockers 8 being adapted to coact with contacts 10 of posts 11 carried on said plate to make and break the armature circuit, said rockers being operated by cam 4. In the illustration shown, the contacts 10 through their posts 11 are connected by wires 12 (carried along the back of plate 2) 95 with contact 13 secured on the back of plate 2, and the rockers 8 are respectively in circuit with plates 14 on the back of plate 2 by wires passing through said plate. This particular arrangement of contacts of the 100 make and break circuit are not broadly claimed herein as they are embraced in my application for improvements in ignition

devices filed March 23, 1909, Serial No. 485,252, my present improvements relating to improved means for supporting and insulating certain contacts in the circuit of the plates 13 and 14. To this end I provide an insulating plate 15 having contacts or springs 16 laid against said insulator, the upper ends of said contacts being shown bent over the end of insulator 15, screws or rivets 17 passing through said contacts 16 and insulation 15 and through plate 1 serving to secure said insulation and contacts to said plate. On the inner face of plate 1 are substantially semi-circular contacts 18 mounted upon insulation 19 on plate 1, and separated or insulated from each other, the screws or rivets 17 connecting with contacts 18 respectively, whereby the parts 15, 16, 17 and 18 are all mechanically and electrically united. Springs or contacts 20, 20^a (suitably supported on the magneto) bear upon the contacts 16 and form part of the primary circuit of the magneto armature, and plates 14 play upon and in contact with springs 20, 20^a. Another spring or contact 21, supported by the magneto, is substantially parallel with contacts 20, 20^a and is in engagement with contact 13, serving as a common return. The arrangement is such that contacts 14 remain in engagement with contacts 20, 20^a, and contact 13 remains in engagement with contact 21, when plate 2 is rocked, and the insulation 15, which may have a spring tendency toward contacts 20, 20^a, serves to maintain the latter in circuit with contacts 16. The contacts 20, 20^a are to be included in the line of circuits of the primary of the armature of the magneto and contacts 18 are maintained respectively in said circuit.

A protecting cap or shell 22 is shown carried by plate 2 and removably attached thereto by posts 23 extending from said plate. Said cap carries a binding post 24 in circuit with shaft 3 by any suitable means, such as brushes 24^a.

Other parts of the circuits are not herein shown as they may be arranged in any well-known manner or as set forth in my application Serial No. 485,252 aforesaid.

While I have shown both guides 5 as adapted to be swung relatively to plate 2, it will be understood that but one of said guides need be movable, as the other guide 5 can be permanently secured or attached to the plate 1, and other changes may be made

in the details of construction set forth, within the scope of the appended claims, without departing from the spirit of the invention.

Having now described my invention what I claim is:—

1. The combination of a support, a plate mounted to rotate thereon, make and break contacts carried by said plate, and guides to 60 movably retain said plate upon said support, one of said guides being movably attached to the support to permit removal of said plate from said support.

2. The combination of a support, an insulating plate rotatively mounted thereon, and provided with make and break contacts, said plate having projections, guides carried by said support to coact with said projections, and means to permit movement 75 of one of said guides for releasing said projections from said guides.

3. The combination of a support, an insulating plate rotatively mounted thereon and provided with make and break contacts, 80 said plate having projections, and guides carried by said support to coact with said projections, one of said guides being movably connected with said support.

4. The combination of a support, an insulating plate rotatively mounted upon said support and provided with make and break contacts, said plate having projections on opposite sides, guides carried by said support on opposite sides to coact with said 85 projections, one of said guides being movably carried by said support, and means to hold said guide firmly in normal position.

5. The combination of a support, a plate rotatively mounted thereon and provided 95 with make and break contacts, said plate having projections on opposite sides, guides carried by said plate on opposite sides and projecting in the same direction to coact with said projections, one of said guides being movably supported at its lower end to release the corresponding projection, and means to hold said guide in normal set position.

Signed at New York city, in the county 105 of New York, and State of New York, this 28th day of June, A. D. 1910.

THEODORE HUBERT.
